G. C. Loening INVENTOR
BY
J. J. Lamb ATTORNEY

UNITED STATES PATENT OFFICE.

GROVER C. LOENING, OF NEW YORK, N. Y.

AMPHIBIAN AIRPLANE.

Application filed April 16, 1926. Serial No. 102,370.

The invention relates to amphibian airplanes, for example such as disclosed in my Patent No. 1,545,505, dated July 14, 1925, designed to land or alight on, and rise from, land or water, irrespective of conditions, also, of mud, sand, snow, vegetable growths, etc., one and the same machine being at home under all terrestrial conditions for which land-planes or seaplanes may, respectively, 10 be adapted, without complication or loss of efficiency in either field. The purpose of the present invention is to provide in such a machine a combination affording a landing (and take-off) gear of very great simplicity 15 and efficiency for all purposes, which is equally a protection for the side-floats and hull on land or, in the water, against floating ice and driftwood.

In the accompanying drawing illustrating 20 the invention, and forming part hereof:

Fig. 1 is a front elevation of a machine embodying the invention, with the propeller omitted; and

Fig. 2 is a side elevation thereof.

25 The machine is of the kind having a central boat-body 2 and side-floats 3, supported from and beneath the outer portions of the wings 4 which extend laterally from the body, the bottoms of the floats being 30 considerably above the level of the bottom of the boat body. As my patent aforesaid, the forward portion 5 of the central hull is shown extended forward as a nose below the tractor propeller 6, the latter being driven 35 by an inverted engine 7 on the forward part of the upward extension 8 of the hull.

In the center line of the hull, approximately at the center of gravity, a single downwardly-opening wheel pocket 9 is formed, 40 and in this pocket there is mounted a single, very substantial landing-wheel 10. This wheel, provided with a large pneumatic tire 11, need not, and preferably is not, otherwise 45 yieldingly mounted, and in any event is a fixed-position, i. e., non-retractible, wheel, all the complication and possible uncertainty of retractible landing gears being avoided, at the same time the hull structure and its internal arrangements are simplified and improved by having only one wheel pocket. A 50 housing 12 extended downward from the hull part way in front of the central wheel reduces water drag.

Supported with each of the under-wing 55 side-floats 3, by the same framing and

brackets, is a stream-line staff 13. Each of these staves is shown universally pivoted at 14 at the forward lower corner of the framing 15 of its float, the upper part of the staff being restrained by elastics 16, and 60 the lower part curving downward and rearward a considerable distance beneath the float, but having its lowest portion above the tread plane of the central wheel 10, and preferably, also, somewhat rearwardly of the 65 wheel. The lateral angle between the horizontal and lines drawn from the tread-point of the wheel to the shoes 17 of the staves should be in the neighborhood of 6°—10°, as indicated in Fig. 1. The shoes 70 17 forming the terminals of the staves are massive stream-line bodies designed to withstand the maximum wear in the service of the staves as runners upon the ground.

The staves function in the water as guards 75 or fenders for the side-floats against ice and drift-wood and save their bottoms and under keels from injury on rocky beaches and in the rough on land. Also, the central wheel 80 constitutes a guard for the under keel of the main hull, its slight projection adding inconsequentially to head-resistance in the air or to drag in the water. In landing on land, the staves act as balancers in conjunction 85 with the central wheel, giving a better landing than two-wheel gears, particularly when landing in a cross wind, the balancing checks acting first at one side and then at the other. The elevated positions of the side-float staves 90 relative to the center-wheel in the hull likewise avoids undue drag either when hydroplaning off the water or when taking off on land. The central wheel permits the machine to be readily pivoted about, and its size and manner of support in the hull prevents sinking in to more than slight depth 95 in soft sand or mud.

What I claim as new is:

1. In an amphibian airplane, the combination of a central flotation body having 100 a central wheel pocket, a central landing-wheel supported in said pocket, side-floats supported from and beneath the wings, and side-float protection members mounted with the side-floats to serve alternately as landing 105 balancers in conjunction with the central wheel, substantially as set forth.

2. In an amphibian airplane, the combination of a central flotation body having 110 a central wheel pocket, a central landing-

wheel supported in said pocket, side-floats supported from and beneath the wings, and staff members mounted yieldingly at the fronts of said side floats and curving 5 downward and rearward as runners beneath the floats and above the tread plane of the central wheel, substantially as set forth.

3. In an amphibian airplane, the combination of a central flotation body, a housing in the bottom thereof a central landing-wheel therein, side-floats, and staff members 10 arranged to protect said side-floats and to serve as landing members in conjunction

with the central wheel, substantially as set forth.

4. In an amphibian airplane, the combination of a central flotation body, a housing in the bottom thereof a central landing-wheel therein, and staff members mounted yieldingly beneath the outer portions of the 15 wings, constituting landing balancers, said staff members being supported with their ground portions above the tread plane of said wheel forming lateral base angles for tilting on land, substantially as set forth.

GROVER C. LOENING.
